UNITED STATES PATENT OFFICE.

DANIEL A. DRISCOLL, OF BUFFALO, NEW YORK.

TOILET-POWDER CASE.

1,077,459.

Specification of Letters Patent.

Patented Nov. 4, 1913.

Application filed March 22, 1912. Serial No. 685,607.

To all whom it may concern:

Be it known that I, DANIEL A. DRISCOLL, a citizen of the United States, residing at Buffalo, in the county of Erie and State of New York, have invented certain new and useful Improvements in Toilet-Powder Cases, of which the following is a specification.

My invention relates to improvements in 10 toilet powder cases, and is designed to provide a case for containing a variety of different toilet powders, and means for independently dispensing these powders.

By the utilization of my invention I 15 eliminate many objectionable features encountered when such toilet powders as for instance, shaving powder, tooth powder, and a talcum powder are carried in separate containers. My invention contemplates a compact, neat, and serviceable case for containing and dispensing the above named powders, that will prove highly desirable in many circumstances.

The invention consists essentially in a container for powders, of standard marketable type from which various powders may be dispensed independently, and in certain combinations and arrangements of parts as will be hereinafter described.

30 In the accompanying drawings I have illustrated one complete example of the physical embodiment of my invention constructed according to the best mode I have so far devised for the practical application 35 of the principles.

Figure 1 is a vertical longitudinal, sectional view of a toilet case involving the invention. Fig. 2 is a sectional view on line 2-2 Fig. 1. Fig. 3 is a plan view of the 40 toilet case, and Fig. 4 is a horizontal sectional view on line 4-4 Fig. 1.

In the preferred embodiment of my invention, the container 1 exemplified in the drawings is a receptacle or can, preferably metallic, constructed in suitable manner, and conforming in general shape to the standard toilet powder cans, although of course it will be understood that the shape of the case may be varied at will.

50 The case 1 is open at its upper end, and is formed with an exteriorly projecting rib 2. The case is preferably formed with a plurality of compartments or chambers, in this instance three such compartments as 3, 4, 55 and 5, being illustrated, but this number may

be varied and a greater or lesser number of compartments be used.

The compartments are formed, in connection with the side and end walls of the case 1, by means of a pair of partitions 6 and 7 60 which are soldered or otherwise secured in the case and extend from the bottom 8 to the open top of the case.

The open top of the case 1 is closed by means of the cap or cover 9, preferably 65 formed with the usual flange 10 to abut against the rib 2 of the case. Attached, (as by solder) to the inside of the cover 9 are a pair of partitions 11 and 12, which are spaced apart a distance sufficient to permit 70 them to close over the open end of the compartment 4. Thus it will be seen that the cover 9 closes the open upper end of each of the compartments, and the partitions 11 and 12 effectually segregate the contents of 75 the compartments from each other, and thus prevent objectionable mixing of powders.

The cover 9 is provided with a series of apertures or openings for dispensing the contained powders. Thus a narrow slot, as 13 80 and a similar slot 14 are cut in the cover over compartments 3 and 5 respectively, and a series of perforations 15 are punched in the cover over the compartment 4. A slide plate 16 is provided with complementary 85 slots 13' and 14' and a series of apertures or perforations 15' to coincide with the apertures in the cover. This slide plate may be moved to cover or expose any of the apertures in the cover, by pressure of the thumb 90 on either of the curled ends 17, 17, and the movement of the plate is limited by means of the teats or projections 18, 18 struck up from the metal of the cover. A pair of side flanges 19, 19 forming grooves and soldered 95 or otherwise fixed to the cover, extend over the slide plate sufficiently to prevent displacement of the plate.

The function of the slide plate is obvious. To dispense talcum powder from the center 100 compartment, the slide plate is moved to the right in Fig. 3 until the perforations 15' register with the apertures 15 and the talcum powder may be dispensed from the can as usual. By the same manipulation, powder may be dispensed from the other compartments.

From the above description taken in connection with the drawings it is evident that I have provided a dispensing container that 110

fulfils the functions and requisites of a comparatively perfect device of this character.

Having thus fully described my invention what I claim as new and desire to secure by 5 Letters Patent is:

As an article of manufacture a case having a plurality of intermediate cross partitions forming a plurality of aligned compartments, a cover having a plurality of 10 cross partitions overlapping said first mentioned partitions, and an outer flange, and having openings to register with said compartments; parallel flanges forming a guide way mounted on said cover, and a slidable

plate having openings coöoperating with said 15 openings in the cover; the openings in the plate being so positioned that when the openings of any one compartment are in alignment with the openings in the plate, the openings in all the other compartments are 20 closed.

In testimony whereof I affix my signature in presence of two witnesses.

DANIEL A. DRISCOLL.
